DESIGN FOR A COMBINED BOTTLE AND CAP

Monroe B. Lukather, Van Nuys, Calif.

Application September 28, 1944, Serial No. 115,497

Term of patent 14 years

(Cl. D58—8)

To all whom it may concern:

Be it known that I, Monroe B. Lukather, a citizen of the United States, residing at Van Nuys, in the county of Los Angeles and State of California, have invented a new, original, and ornamental Design for Combined Bottle and Cap, of which the following is a specification, reference being had to the accompanying drawing, forming part thereof, in which:

I claim:

The ornamental design for a combined bottle and cap, as shown.

MONROE B. LUKATHER.
